CLAIM

The ornamental design for a server unit, as shown and described.

DESCRIPTION

FIG. 1 is a front view of a server unit showing our design; FIG. 2 is a perspective view thereof; and, FIG. 3 is a perspective view of another server unit showing our design.

The broken lines in the drawings illustrate portions of the server unit or environment and form no part of the claimed design.

1 Claim, 3 Drawing Sheets

FIG. 1

FIG. 2

FIG. 3
